UNITED STATES PATENT OFFICE.

JAMES RANDALL, OF NORWICH, CONNECTICUT.

DANDY-ROLL FOR PAPER-MACHINES.

SPECIFICATION forming part of Letters Patent No. 249,992, dated November 22, 1881.

Application filed October 25, 1881. (No model.)

To all whom it may concern:

Be it known that I, JAMES RANDALL, a citizen of the United States, residing at Norwich, in the county of New London and State of Connecticut, have invented a new and useful Improvement in Dandy-Rolls for Paper-Machines, of which the following is a specification.

My invention relates to the class of rolls for water-marking paper called "dandy-rolls," in which certain marks are impressed upon the moist and soft paper as it is passed under them.

My object is to do away with separate rolls for each mark or design required, and thus greatly lessen the expense, and to so balance my peculiar roll as that it shall bear very lightly upon the paper; and my invention consists of a roll made up of separate sections or interchangeable forms, with its journals resting upon the short ends of levers with adjustable weights. The mechanism by which I attain this is shown in the accompanying drawings, in which—

Figure 1 is a plan view of the parts of the roll locked together ready for use. Fig. 2 is a view of the compound or composite roll with two of its sections removed.

Similar letters refer to similar parts in the different views.

A is part of the frame-work or machine upon which the improved dandy-roll is mounted.

B is one of the two slotted standards in which the journal of the roller-shaft turns.

C denotes the entire roll, made up of its several sections.

D and F are the end disks forming the frame upon which the roll-sections are mounted, and adjust laterally to admit longer or shorter roll-sections.

E is a central movable disk, provided with small pins *a*, that enter corresponding holes in the ends of the roller forms or sections.

G G represent two levers that support the journal *f* of the roll. The levers are fulcrumed in the posts B, furnished with a series of holes, *g*, for pinning the said levers.

H H are the weights, adjustable along the levers.

K L M N are the four sections that go to make up the roll.

P is a flanged cap, that is turned forward upon the screw-ended journal after the sections are in place to hold them firmly.

Until quite recently separate dandy-rolls for water-marking were required for each name or design; hence the rolls were often multiplied to the number of several hundred. These rolls were expensive, as each one required a carefully-adjusted central journal-shaft. They took up, from their form, necessarily a large place for storage. My object is to have interchangeable and removable forms used upon a single journal and its disks, or "spiders," as they are sometimes called. These forms, being sections of a hollow cylinder, readily pack away in a comparatively small space. Each one of the forms may contain all the letters or designs needed, and be used with others that have no letters. The form is made of thin perforated metal, with end pieces of thicker material. The two forms H and M may be placed first in position, the pins *a* passing into holes in their ends. After these two are in position the sustaining-disk E is pushed along its journaled shaft until its pins enter holes in the inner ends of the forms. The forms L and N are then secured to the pins on the outer side of disk E. After these two are in position the flange-cap P is screwed up until it catches over the correspondingly-flanged ends of the forms, as seen at *t*, Fig. 2.

It will be readily seen as the holding disks E and D adjust on the journal-shaft that forms of different lengths may be used, and that these forms may make cylinders of varying diameters, the different sizes resting readily upon the same disk-pins.

I have shown pins in the disks entering holes in the form ends; but it is, of course, evident that the pins may be in the forms and the holes in the disks.

It is evident also that projections or tenons extending laterally from the ends of one set of forms may enter corresponding holes or recesses in the ends of a second set.

The designs or letters are small wire, soldered upon the perforated metal surface of the forms in the usual way. As there is nothing new in this, the letters have not been shown in the drawings. A large number of these cheaply-made forms can be kept on hand, and only

one journal-shaft with disks is needed. In the old form of dandy-roll, if any accident occurred the cloth had to be taken off to remedy it; but in my new form of roll, upon unscrewing the 5 single cap P at one end the forms are easily loosened and removed.

In order that my roll may rest lightly upon the paper, I rest its journal-ends on levers and adjust the exact pressure wanted by means of 10 weights adjustable on the longer ends of the levers.

It is quite evident that exactly the same result may be accomplished by attaching weights and cords to the journals or by resting the 15 journals on springs that may readily be adjusted for various weights, the only requisite being that the roll shall be counterbalanced so as to bear lightly upon the paper. It is especially necessary in a dandy-roll that it do not 20 bear heavily upon the paper. With my balancing-levers, or their equivalents in weights or springs, a roll of fifty pounds may be made to run over the paper as lightly as the ordinary small dandy-roll formerly used. A balancing 25 device of some sort—and it may be of any well known to mechanism—is a very important addition to a compound roll, which is, from the nature of things, somewhat heavy.

I am aware that springs are used to vary and 30 add to the weight of rolls in various mechanical devices; but no dandy-roll has ever been balanced to reduce its pressure.

I am also aware that various devices have 35 lately been invented to replace the old dandy-roll, such devices consisting of reversible letters placed upon forms that rock or partially

rotate upon the paper; but it is found in practice that a continually-rotating cylinder is preferable.

I do not broadly claim a composite marking 40 device or one made up of sections; but

What I claim is—

1. A dandy-roll made up of removable and interchangeable sections, upon which distinct devices may be made, the several sections 45 when united forming of themselves a complete and perfect cylinder-surface, all as and for the purposes set forth.

2. In a water-marking roll composed of various sections or parts of cylinders, the combination of the central shaft or journal and the movable retaining-disks adjustable for varying lengths of forms, all as described. 50

3. The combination, with a water-marking roll made up of removable sections, of the slotted standards B, the lever G, for sustaining the ends of the journal, and the adjustable weight H, all as described. 55

4. In a water-marking roll composed of removable sections, the combination of the flange 60 t and the flanged cap P, screwing upon the journal to secure the forms, all as and for the purposes described.

5. In combination with a dandy-roll for water-marking, made substantially as described, 65 levers and weights for counterbalancing it, all as and for the purposes set forth.

JAMES RANDALL.
